Fig. 5

FIGURE 1 is a top plan view of a compartmented candy tray, showing my new design with the right half shown in broken lines for convenience of illustration being a continuation of the pattern shown by the left half;

FIGURE 2 is a side elevational view;

FIGURE 3 is an end elevational view;

FIGURE 4 is an enlarged fragmentary top plan view; and

FIGURE 5 is a sectional view taken substantially on the line 5—5 of FIGURE 4.

The design is characterized by a one-piece tray molded with a horizontal marginal flange having an embossed upper surface and a marginal groove in said flange, all as shown.

I claim:

The ornamental design for a compartmented candy tray, as shown and described.
